(57) **CLAIM**

The ornamental design for a winch system, as shown and described.

DESCRIPTION

FIG. 1 is a front, right, top perspective view of a winch system, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the winch system, shown in a condition of use; and,

FIG. 10 is a partial enlarged view of FIG. 9.

The dash-dot-dash broken lines are for notating enlarged views and form no part of the claimed design.

The dashed broken lines in the FIG. 9, FIG. 10 are for the purposes of indicating the usage environment of the winch system and form no part of the claimed design.

1 Claim, 10 Drawing Sheets
